UNITED STATES PATENT OFFICE.

THOMAS SPAULDING, OF LOS ANGELES, CALIFORNIA.

AUTOMATIC NOISELESS RAILWAY-CROSSING.

1,367,837.

Specification of Letters Patent.

Patented Feb. 8, 1921.

Application filed August 8, 1919. Serial No. 316,223.

To all whom it may concern:

Be it known that I, THOMAS SPAULDING, a citizen of the United States, residing at Los Angeles, in the county of Los Angeles, State of California, have invented new and useful Improvements in Automatic Noiseless Railway-Crossings, of which the following is a specification.

My invention has relation to railway crossings of the wheel-operated type, although it is susceptible to operation by other means, and it is an object of this invention to provide a railway crossing practically noiseless in its operation and which cars may pass over without the jar and noise incident to the use of the prevailing type.

Another object is to provide a railway crossing having turn-tables, located at the rail intersections, designed to be rotated by the action of laterally moving levers pivoted beside the rails and adapted to come into contact with the flanges of the car wheels.

Another object is to provide a railway crossing having turn-table members at the rail intersections, each of the turn-tables carrying a tread, or rail section, and having a flange-way on each side of the tread to permit operative alinement of the tread with the intersecting rails whether the turn-table be rotated to the right or to the left.

Another object is to provide a railway crossing having turn-table members at the rail intersections, each of the turn-tables carrying a tread with a flange-way on each side of the tread, and the sides of the tread converging toward each end to allow clearance for the wheel flange in event of lost motion in the operation of the mechanism of the crossing.

Another object is to provide a railway crossing having turn-table members which are interchangeable and readily removable for replacement or repair.

Another object is to provide a railway crossing having at the rail intersections turn-table members detachably connected to rotary disks beneath the rails, which rotary disks carry adjustable channels or guides by means of which the motion is transmitted to the rotary disks from the levers pivoted beside the rails.

Another object is to provide a railway crossing having turn-table, or rotary frog, members at the rail intersections and V-shaped joints in the adjacent rails to pre-

vent the expansion of the rails from binding the rotary members against movement, as well as to prevent the contraction of the rails from opening such gaps at the joints as would cause jar and noise from passing cars.

With these and other objects in view the invention consists in the construction and novel combination and arrangement of parts hereinafter fully described, illustrated in the accompanying drawings and pointed out in the claims.

In the accompanying drawings:

Figure 1 is a plan view showing intersecting railway tracks with this invention applied thereto.

Fig. 2 is a perspective view showing construction details at one of the intersections and the means for counteracting the effects of contraction and expansion of the rails.

Fig. 3 is a perspective view showing the rotating mechanism, one of the intersecting rails being omitted.

Fig. 4 is an elevation at intersection B the turning mechanism of which is operated by means of a lever connected to a rotating device at intersection A.

Fig. 5 is a perspective view showing a modification in the application of the actuating lever for a direct-operating intersection, such an intersection being one at which are located surface levers adapted to be engaged by the flanges of the passing wheels.

Fig. 6 is a vertical section on the line x-x of Fig. 3.

Like numerals of reference designate corresponding parts in the several figures of the drawings.

More specifically in the drawings 7-7' represent the rails of one track and 8-8' represent the rails of another track crossing the first mentioned track at a right angle, the intersections being designated by the letters A, B, C, and D, respectively. At each intersection is mounted a turn-table 9 having a vertical stem or axis 10. On the upper side of each turn-table is formed a tread 11 with narrowing ends and having flange-ways 12 and 13 on opposite sides. Turn-table 9 is supported by collar 14 which rests on base-plate 15, the base-plate being supported by cross-ties or other suitable means. Short rail sections 16 and 17 are provided between the turn-tables and the main rails said short rails having their tread portions at the outer ends formed V-shaped

as shown at 18 and 19 the apexes of the V-shapes being preferably pointed in the direction from which the greater volume of traffic approaches. The web at the outer 5 end of each of the short rails is enlarged to provide a supporting shoulder as indicated at 20 on which rests the extended portions of the treads of the main rails, which are cut to fit the outer ends of the short 10 rails.

Beside the rails are pivoted at 21, 22, 23, and 24 the primary levers 25, 26, 27 and 28, respectively, and beyond the free ends of these primary levers are pivoted at 29, 30, 15 31 and 32 the secondary levers 33, 34, 35 and 36, respectively. Arms 37 are rigidly attached to each of the primary levers and arms 38 are similarly attached to each of the secondary levers. Flexible connection is 20 maintained between arms 37 and 38 by means of the pin and slot formation as indicated at 39. The primary and secondary levers, in vertical cross section, are of inverted L formation, substantially, the horizontal 25 portion being curved to provide the lever greater range of action and is adapted to overlap the rail (see Fig. 6) when the lever is in closed position. Primary levers 25 and 26 are each provided with rigid extensions 30 40 and 41, respectively, which are projected downward and forward to engagement with the rotating mechanism.

At intersections designated A, B and C bell-crank levers 42, 43 and 44, respectively, 35 are pivoted on the axes or stems 10 of the turn-tables, said bell-crank levers resting on brackets 45 which are attached to the base-plates. The arms of bell-crank lever 42 are turned up at their outer ends and project 40 through slots 46 and 47 in levers 25 and 27, respectively, and, similarly, the arms of bell-crank lever 44 project through slots 48 and 49 of levers 26 and 28, respectively. Rods 50 and 51 connect bell-crank levers 42 and 45 44 with bell-crank lever 43.

Below brackets 45 and attached to the base-plates are brackets 52 on which are pivoted rotary disks 53 provided with centrally located, upward projecting stems 54 50 to which axes 10 of the turn-tables are detachably connected by means of tongue and groove formations as indicated at 55.

At intersections A and C stems 54 are each cut away to their centers on one side near 55 their lower ends, as indicated at 56, to permit the passage of extensions 40 and 41 of actuating levers 25 and 26 along lines bisecting the centers of stems 54.

Rotary disks 53 at intersections A and C 60 carry on their upper surfaces guides, or channels, in two sections 57 and 58. Channel 57 is preferably rigidly attached to disk 53, while channel 58 is pivoted at 59 and adjustable by means of screw 60 to permit 65 arrangement of the two channel sections so

their relation to each other will conform to that of the intersecting rails above. One end of screw 60 is supported in eye-bolt 61 which is mounted on disk 53 and adapted to turn as necessary in changing the position 70 of channel 58. The other end of screw 60 is pivotally connected to channel 58.

The turn-table at intersection B is operated by means of rod 62 connecting disks 53 at intersections B and A, and, similarly, 75 the turn-table at intersection D is operated by means of rod 63 connecting disks 53 at intersections C and D.

A modification in the application of the actuating lever is shown in Fig. 5 which 80 permits of reducing the range of movement of the primary lever 64, the desired range of movement being obtained for the extension 65 by providing the required length for the extension 65 below the point 66 at which 85 it is pivoted.

The secondary levers would be necessary in case a car should stop on the crossing after one or more pairs of wheels had passed over the near intersections and was then 90 obliged to back up. If meanwhile the turning mechanism had been operated to throw the treads on the turn-tables out of alignment with the rails on which the car stood the secondary levers would insure the res- 95 toration of a clear passage.

It will be apparent the bearings may be made adjustable to prevent lost motion and that suitable hand-holes near the intersections will permit of removing and replacing 100 worn parts without the necessity for excavating after the crossing is in place. The facility with which positively operated signals may be connected with the rotating mechanism to show the position of the crossing as to closed or clear track is obvious.

From the foregoing the operation of the device will be readily understood by those skilled in the art. It is evident that one of the wheels on the first truck of a car 110 approaching the crossing on either track will, if the turn-tables are not in proper position for the car to pass over properly, come into engagement with one of the primary levers the lateral movement of which will open the 115 flange-ways to the approaching wheels and at the same time close the flange-ways on the other track through the operation of the bell-crank levers and the primary and secondary levers. The resulting action of the exten- 120 sions of the primary levers in the channels will rotate the disks and turn-tables simultaneously and thereby place the tread on the turn-table at each intersection in alignment with the rails on which the car approaches. 125

The positions of the various parts will thereafter be maintained until a car approaches to operative position on the other track when the alignment will be similarly accomplished to accommodate traffic on that track. 130

Various alterations and modifications in construction and arrangement of the parts are possible within the scope of this invention and I do not, therefore, wish to be considered restricted to the precise construction and arrangement here shown.

I claim:

1. In a railway crossing, the combination with pairs of intersecting rails, turn-tables 10 mounted at the points of intersection, said turn-tables having on their upper surfaces treads narrowing at each end, a flange-way on each side of the tread and means for bringing the treads into alignment with the 15 rails of the intersecting tracks.

2. In a railway crossing, the combination with pairs of intersecting rails, turn-tables at the intersections, treads and flange-ways on the upper surfaces of the turn-tables, 20 rotary disks mounted near the turn-tables and connected therewith, guides attached to the rotary disks and means for rotating the disks.

3. In a railway crossing, the combination 25 with pairs of intersecting rails, turn-tables at the intersections, treads and flange-ways on the turn-tables, rotary disks mounted below the turn-tables and connected therewith, sectional channels mounted on the rotary 30 disks, means for altering the positions of the different sections of the channels with relation to each other and means for turning the rotary disks.

4. In a railway crossing, the combination 35 with pairs of intersecting rails, turn-tables at the points of intersection, treads on the upper surfaces of the turn-tables, said treads narrowing toward their ends, wheel flange-ways on each side of the treads, rotary disks 40 near the turn-tables and connected therewith, adjustable guides mounted on the rotary disks, laterally movable levers pivoted beside the rails, extensions of these levers projected into operative engagement with the 45 guides and means for transmitting motion to the various intersections.

5. In a railway crossing, the combination 50 with pairs of intersecting rails, turn-tables at the points of intersection, treads on the upper surfaces of the turn-tables, said treads being narrowed toward their ends, wheel flange-ways on each side of the treads, rotary disks below the turn-tables and connected therewith, adjustable channels mounted on 55 the rotary disks, laterally movable primary levers pivoted beside the rails, secondary levers pivoted beside the rails beyond the free ends of the primary levers, flexible connection between the primary and secondary 60 levers, extensions of the primary levers into operative engagement with the channels on the rotary disks and means for connecting the operating mechanism at the various intersections.

5. 6. In a railway crossing, the combination

with pairs of intersecting rails, turn-tables at the points of intersection, treads and wheel flange-ways on the turn-tables, laterally movable levers beside the rails said levers being each pivoted at one end and having 70 their upper portions turned to a horizontal plane and adapted to overlap the adjacent rails when the levers are in closed positions, curved edges on the horizontal portions of the levers, means for transmitting the motion 75 of the levers to the turn-tables and means for connecting the operating mechanism of the various intersections.

7. In a railway crossing, the combination with pairs of intersecting rails, turn-tables 80 mounted at the points of intersection, treads and wheel flange-ways on the turn-tables, primary levers pivoted beside the rails, operative connection between the primary levers and the turn-tables, bell-crank levers 85 mounted at the intersections and connecting the primary levers and means for connecting the bell-crank levers to each other.

8. In a noiseless railway crossing, the combination with pairs of intersecting rails, 90 turn-tables mounted at the points of intersection, treads and wheel flange-ways carried on the turn-tables, short rail sections adjacent to the turn-tables, V-shaped formation of the treads of the short rail sections at 95 their ends distant from the turn-tables, enlarged webs beneath the treads at the outer ends of the short rail sections, supporting shoulders formed on the upper portions of the enlarged webs and V-shaped formations 100 of the treads at the ends of the main rails, where they connect with the short rail sections, said V-shaped formations of the main rails and short rail sections being adapted to fit together. 105

9. In a railway crossing of the character described, the combination with pairs of intersecting rails, a base-plate at one of the intersections and main rail ends resting thereon, short rail sections resting on the 110 base-plate at the end of and in alignment with each main rail and forming a continuation thereof, V-shaped formation of the treads at the outer ends of the short rail sections, enlarged webs at the outer ends 115 of the short rail sections, shoulders formed on the enlarged webs, V-shaped formation of the tread portions of the main rails at their junctions with the short rail sections, said tread portions being under-cut and resting on the shoulders of the enlarged webs, a collar having downwardly diverging sides mounted on the base-plate between the short rail sections, a turn-table resting on the collar and having a depending cylindrical stem 120 extending through the collar and base-plate, a tread narrowing toward each end formed on the upper surface of the turn-table, wheel flange-ways on each side of the tread, primary levers each pivoted at one end for 125 130

4

lateral movement beside the rails, secondary levers beyond the free ends of the primary levers and each pivoted at one end for lateral movement, flexible connection between the primary and secondary levers, said primary and secondary levers having their upper portions turned to a horizontal plane and adapted to over-lap the adjacent rails when the levers are in closed positions, 10 curved edges on the horizontal portions of the primary and secondary levers, a bell-crank lever supported on a bracket beneath the base-plate and pivoted on the stem of the turn-table the extended arms of the bell-crank lever being turned up near their ends 15 and projecting through slots in the base-plate to engagement each with one of the primary levers, a second bracket attached beneath the base-plate, a rotary disk pivoted on the bracket, an upwardly projecting centrally located stem rigidly attached to the rotary disk, detachable connection between the stem of the turn-table and the stem of the rotary disk which latter stem 20 is cut away to the center on one side near its junction with the rotary disk, an adjustable channel attached to the rotary disk, and a rigid extension of one of the primary levers maintaining operative engagement 25 with the channel; at the diagonally opposite intersection a construction and arrangement of parts similar to that described above, at each of the two remaining intersections a base-plate, short rail sections connected to 30 the main rails, a turn-table and second bracket, as described above, a rotary disk 35

mounted on the bracket said rotary disk having a centrally located upward projecting stem to which the stem of the turn-table is detachably connected, a rod having one end pivoted on the rotary disk and its other end similarly pivoted on the rotary disk at an adjacent intersection; at one of the last two mentioned intersections a bracket supporting a bell-crank lever pivoted on the 40 stem of the turn-table, and rods connecting each arm of the bell-crank lever to a bell-crank lever at an adjacent intersection, all substantially as described. 45

10. In a construction of the character described, the combination with pairs of intersecting rails, short rail sections near the points of intersection said short rail sections having at their ends most distant from the intersections V-shaped formations of their treads, enlarged webs supporting the V-shaped tread portions, shoulders formed on the enlarged webs, V-shaped formations of the treads of the rails immediately connecting with the short rail sections, such V-shaped formations of the short rail sections and connecting rails being adapted to fit together and means for providing practically continuous treads at the intersections for each of the intersecting tracks as desired. 50 55 60 65

In witness that I claim the foregoing I have hereunto subscribed my name this first day of August, 1919.

THOMAS SPAULDING.
